CLAIM

The ornamental design for a trellis, as shown and described.

DESCRIPTION

FIG. 1 is a top perspective view of a trellis showing our new design.

FIG. 2 is a bottom perspective view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

The broken lines in the Figures show environment or portions of the trellis that form no part of the claimed design. The shade lines in the Figures show contour and do not claim surface ornamentation or treatment.
